UNITED STATES PATENT OFFICE.

ELIAS W. SEYMOUR, OF LISLE, NEW YORK.

IMPROVEMENT IN METHODS OF CONSTRUCTING CARRIAGES.

Specification forming part of Letters Patent No. 35,204, dated May 6, 1862.

To all whom it may concern:

Be it known that I, ELIAS W. SEYMOUR, of Lisle, Broome county, and State of New York, have invented certain Improvements in Constructing Wagons, the operation of which I have described in the specification and illustrated in the accompanying drawing with sufficient clearness to enable competent and skillful workmen in the arts to which it pertains or is most nearly allied to make and use my invention.

My improvement is intended principally for the construction of light wagons.

My said invention consists in the arrangement of springs running lengthwise and fastened behind to the axle and to a spring-bar or spring in front supported by a relieving-bar having a joint at each end and attached to the axle behind, running parallel with the springs and fastened to the center of each spring on the under side and in front. Said springs are supported by the boot fastened to the spring-bar or spring, and also to the under side of the seat, by a joint. The said springs, relieving-bar, and boot constitute all the parallel gearing of the wagon, and by means of my invention the boot moving with the spring or being hung by said joints under the seat is so arranged as to add to the comfort of the wagon and materially diminish its weight.

The figure is a side view of the wagon, and is designed to show fully my invention.

a a are the springs running parallel.

c c show the fastenings of the said springs to the hind axle-tree of the wagon.

g shows the fastening of the springs to the spring-bar or spring in front.

b b are the relieving-rods to the back portion of the springs. *d d* are the joints under either spring, to which said rods are attached to the axle behind. *k* is another joint in the center of

the spring, to which the rods *b b* are attached. Said rods are not only to relieve the springs and steady their motion, but serve the purposes of a reach, the draft coming upon said rods behind and the boot in front, when the springs act or are subjected to heavy weight, thus saving the springs from all tension that would otherwise come upon them.

e is the boot which forms the relieving-rods in front, and, together with the dash *h*, constitutes the body of the wagon in front, and is attached to the spring-bar or spring in front on a line with the point *g*, which is the attachment of the springs to the spring-bar or spring in front.

f is the joint under the seat, to which the upper portion of the boot *e* is attached, and when the springs are settled down to a certain point the boot *e* acts in conjunction with the rods *b b* and takes the tension and strain entirely from the springs, and, acting thus from the center of said springs each way, forms, to all intents and purposes, so far as safety and strength are concerned, a continuous reach.

What I claim as my improvement, and for which I desire to procure Letters Patent, is—

The peculiar construction and combination of springs running lengthwise and attached behind to the axle, which is connected with relieving-bars behind and boot acting as relieving-bars in front and operating in conjunction with each other and from the center each way, forming a reach and saving the springs from the tension of draft.

In witness whereof I have hereunto set my hand this 7th day of August, A. D. 1861.

ELIAS W. SEYMOUR.

In presence of—

SAMUEL B. WHITTEMORE,
ORSON O. HODGES.
